TELEGRAPH SYSTEM

Clarence E. Lomax, Oak Park, Ill., assignor to
 Associated Electric Laboratories, Inc., Chicago,
 Ill., a corporation of Delaware

Application November 7, 1935, Serial No. 48,655

5 Claims.

(CL. 178—2)

The present invention relates to telegraph systems in general, but is concerned more particularly with a telegraph system in which special signals are required to be transmitted over a telegraph line to one or more signal stations located along such line.

5 The object of the invention is the production of a new and improved circuit arrangement for preventing the selective switches in the signal stations from operating needlessly responsive to telegraph signals, thereby effecting a considerable saving in wear and tear on the selectors at the signal stations.

General description

15 The invention is directed toward the solution of the problem that arises when one or more signal stations are located along the route of a telegraph line extending between a telegraph transmitting station and a telegraph receiving station. It is desirable to permit the attendant at a desired one of the signal stations to be signalled to perform a prearranged operation, such as temporarily opening the line for test purposes; applying 25 an artificial leakage shunt between the line and earth; removing a previously applied artificial shunt from between the lines and earth; and so forth.

Previously, the desired signalling operations 30 have been carried out by associating a selector with a telegraph line at each of the intermediate signal stations, and permitting the selector to be controlled over the line by all of the signals, telegraphic or otherwise, the selector being arranged so that it selects and completes a selected signal circuit only in the event that special selecting signals differing somewhat from the telegraphic signals are transmitted over the line. While this arrangement has proven to be workable, the selectors used wear out abnormally fast 35 because they respond to the telegraph signals as well as to the special signals which are intended to bring about their operation. This situation will be appreciated more fully when it is recalled 40 that telegraph signals may be transmitted almost continuously for hours at a time over a busy telegraph line, while the special signals may be transmitted for only a few seconds at a time and at relatively rare intervals, perhaps not oftener than on the order of a dozen or so times a day.

50 An arrangement has therefore been devised for placing the signal selectors under the control of the telegraph line only responsive to a special signal not encountered in the routine transmission of telegraph messages. A feature of the arrange-

ment is that as soon as a selector has been operated completely to make a selection it is automatically removed from under the control of the telegraph line.

It has been found convenient to use a prolonged opening of the line as the special signal which indicates that selecting signals, as contrasted with telegraphic signals, are about to be transmitted and to arrange the relay apparatus which controls the signal selectors so that signals transmitted over the telegraph line do not reach the signal selectors unless preceded by the prolonged opening of the line above referred to.

Referring now to the single figure of the accompanying drawing, a telegraph transmitter 1 is indicated diagrammatically as interconnected by telegraph line 5 with telegraph receiver 2, located at the distant end of the telegraph line. Two signal stations, A and B, are shown along the telegraph line.

20 The Strowger selector S₁ is shown at signal station A, and the similar Strowger selector S₂ is indicated at signal station B. Test panel 6 is inserted in the line 5 at station A, while test panel 7 is inserted in the line at signal station B. It is at these test panels that the attendant may perform operations such as set forth hereinbefore, when he is signalled to do so.

25 The normally closed push-button 4 is inserted in the line 5 to produce the prolonged break in the line which signifies that selecting signals, as contrasted with telegraphic signals, are about to be sent. The calling device CD is preferably of the usual finger-hole-dial type commonly used in automatic telephone systems to control the 30 operation of the automatic switches. This calling device has the normally closed impulse contacts (as shown) connected directly in series with the telegraph line for the purpose of transmitting desired predetermined series of interruptions 35 in the line when the calling device is turned in the usual manner and allowed to return to normal position.

At signal station A, the Strowger selector S₁ is of a type well known to those versed in the art 40 of automatic switching. This selector has the usual double-member wiper 38 mounted on a vertically movable and rotatable shaft (not shown) so that it can be brought into operative relation with any desired one of the contacts in the illustrated bank 39. Ordinarily, the contact bank is arranged in ten horizontal rows or levels with ten contacts in each level. Only a few of the bank contacts are shown for illustrative purposes. The vertical magnet 31 is the one which raises 45

55

the wiper 38 opposite the desired level of bank contacts; rotary magnet 32 is the one which rotates it over the selected level until it reaches the desired contact; and release magnet 33 is the 5 one which brings about the restoration of the wiper 38 to its normal position when the release magnet is energized.

The usual conventional showing of the various 10 relays of the selector S1 is made. It may be pointed out that the illustration of release relay 22 indicates that this relay has a copper sleeve placed over the core thereof underneath the winding in order to render the relay slow-releasing by virtue of the magnetic effect produced by 15 the circulating current in the copper sleeve; relay 24 has a copper collar encircling the core on the armature end thereof, as indicated by the solid black upper portion of the relay, so as to render the relay slow in operating responsive to a closure 20 of its circuit; relay 25 has a copper collar placed around the core at the yoke end thereof, whereby the relay is rendered slow in releasing, although it is not as slow in operating as one which has a copper collar on the armature end; and relays 26 25 and 27 are each provided with a conducting sleeve as explained in connection with release relay 22 so as to render them slow releasing. The off-normal contacts 34, 35, and 36 are mounted 30 on the switch in the usual manner so as to move to alternate position when the wiper of the switch is moved from its normal position.

Detailed description

The disclosure having been described generally, 35 a detailed description of the operation of the apparatus shown will now be given. For this purpose, it will first be explained how the relays 21 to 23 interact during the transmission of telegraph signals to prevent a response of the selector S1, it being understood that a similar arrangement is provided at the selector S2.

Relay action during telegraphing

Normally, the illustrated circuit over the 40 telegraph line 5 is closed and current is flowing thereover. Relay 21 of the Strowger selector S1 is therefore in an operated position as shown in the drawing. During the transmission of a telegraph signal the circuit is successively opened 45 and closed at the transmitter for variable lengths of time. If the usual Morse telegraph transmission is used, the well known dots and dashes are transmitted over the line, while if the Baudout code system of transmission is employed (as in 50 printing telegraphy) the signals are sent in coded time relationship, and the length and spacing of the openings in the line are more variable.

When line relay 21 restores during signalling, 55 it closes a circuit through contacts of cut-in relay 25 through the resistor 30 to the negative, ungrounded pole of the local battery used at signal station A, thereby shunting the winding of the slow-acting release relay 22. Relay 22 is slow in restoring because of the circulating current flowing 60 through the conducting sleeve previously mentioned and because of the additional circulating current which flows through its short circuited winding, both actions contributing to retard the decay of the established magnetic flux. 65 As relays of this type are ordinarily constructed, the relay 22 may be expected to remain operated during a large fraction of a second after it has become short circuited. By this arrangement, during much of the time of the transmission of 70 signals, relay 22 does not restore because relay 21

is quickly reoperated, and the current-flow is thereupon reestablished through the winding of relay 22 from the resistor 30. Now it happens occasionally in telegraphic transmission that the open-line period exceeds the release time of relay 5 22, in which case line relay 21 is restored for a sufficient length of time to result in the restoration of release relay 22. When relay 22 restores, it operates the timer relay 23 which closes a circuit for the slow-operating locking relay 24 10 through the weighted-spring contact associated with the armature of relay 23. The weight 37 is attached to the contact spring associated with the armature of relay 23 to cause the contact spring to vibrate rather vigorously for a time 15 after the contact is struck by the armature. Relay 24, by design and adjustment is sufficiently slow in operating that it does not actuate its armature until the vibration of the contact has substantially ceased. This period may conveniently 20 be adjusted at about three seconds in order to insure that relay 24 does not operate until line relay 21 has been restored for a period of at least three seconds. Since the line is never opened for a time as long as this in the regular transmission 25 of telegraph messages, timer relay 23 is always restored to permit the armature to break away from the associated working contact before relay 24 has had time to operate, except under the special conditions of an intentional break in the 30 line for the purpose of placing the selector under the control of the line relay, as will now be described.

Operating the signal-station selectors

It will now be assumed that the attendant or dispatcher at the telegraph transmitting station desires to signal the attendant at one of the signal stations along the telegraph line. In order to condition the selectors S1 and S2 for control 40 over the telegraph line, the dispatcher causes the operation of the telegraph transmitter 1 to cease and he opens the telegraph line at the push-button 4 for a period of several seconds (ten for example), after which he closes the line by permitting the key 4 to restore. He then sends two desired series of impulses over the line by successive operations of the calling device CD.

In the signal station A, when the line is opened by the push-button 4, line relay 21 restores and 50 places a shunt around the winding of slow-acting release relay 22. After a short interval, relay 22 restores and closes an operating circuit for timer relay 23, whereupon the armature of relay 23 strikes its cooperating contact and thereby sets 55 the associated spring into vibration controlled by weight 37. As soon as the vibratory motion of the spring contact has ceased, (after a period of about three seconds), lock relay 24 operates and closes a locking circuit for itself in series with 60 cut-in relay 25, which locking circuit includes the inner contacts of cut-out relay 29. Relay 25 does not operate in the locking circuit of lock relay 24 for the time being because relay 25 is shunted by the initial circuit established for relay 24 through 65 the contacts of relay 23.

The relays remain in this condition (with relays 21 and 22 restored, and with relays 23 and 24 operated) until the push-button 4 at the transmitting station is restored to permit current to 70 flow again over the telegraph line, whereupon relays 21 and 22 reoperate, and relay 23 restores. Timer relay 23, upon restoring, opens the initial circuit of locking relay 24, but relay 24 remains operated in series with cut-in relay 25. Cut-in 75

relay 25 now operates in series with locking relay 24 and through the inner contacts of cut-out relay 29. Upon operating, cut-in relay 25 opens a point in the circuit of release magnet 33 at its lower armature, at the same time preparing to extend ground potential to the wiper 38 of the switch mechanism. At its upper armature relay 25 disconnects the armature of line relay 21 from the junction of resistor 30 and relay 22, and extends it through off-normal contacts 35 and vertical-series relay 36 to the vertical magnet 31, preparatory to the operation of the selector.

With cut-in relay 25 now operated in the locking circuit of relay 24, line relay 21 is now disassociated from relays 22 and 23 and is in association with the mechanism of the selector so as to enable the selector to respond to control impulses transmitted over the line.

As previously stated, the dispatcher at the transmitting station now dials two digits, which operation, it will be understood, consists in placing his finger in the finger hole of the dial corresponding to the number of impulses desired in the first digit; turning the dial around to stop position; and releasing the dial and permitting it to return to normal position by spring action, following which he repeats the operation for the second desired digit.

When the first digit is dialled, the normally closed impulse contacts of the calling device 3 are separated a number of times depending upon the value of the digit. Each time the contacts are separated, line relay 21 at signal station A is momentarily restored.

Each time line relay 21 is restored (under the circuit conditions now existing), a circuit is closed through contacts of the operated cut-in relay 25, off-normal contacts 35, vertical series relay 26, and through vertical magnet 31 to the ungrounded pole of the local battery. The vertical magnet 31 operates to raise the wiper 38 opposite the level of contacts corresponding to the digit dialled. Vertical-series relay 22 is operated upon the delivery of the first impulse to the vertical magnet and prepares a holding circuit for itself which serves to maintain its own circuit and that of the vertical magnet intact after off-normal contacts 35 have shifted, as they do upon the first vertical step of the switch. Also, off-normal contact 36 prepares a circuit for cut-out relay 29, and off-normal contacts 34 prepare a circuit for release magnet 33.

At the end of the series of impulses, vertical-series relay 26 restores and transfers the operating circuit from vertical magnet 31 to rotary magnet 32.

When the next series of impulses is delivered, each resulting restoration of line relay 21 results in the transmission of an impulse through the now-shifted off-normal contact combination 35, contacts of the now-restored vertical series relay 26, and through slow-acting rotary-series relay 27 to rotary magnet 32. Magnet 32 is therefore operated to cause wiper 38 to be rotated into engagement with the desired contacts in the selected level.

When rotary series relay 27 operates it closes a circuit for locking relay 28. Locking relay 28 thereupon operates and closes a locking circuit for itself in series with cut-out relay 29, through the now-closed off-normal contacts 36. Cut-out relay 29 does not operate for the time being because it is short circuited by the initial application of ground potential to the winding of locking relay 28 at the upper contacts of relay 27.

At the end of the series of rotary impulses, slow-acting rotary series relay 27 restores and opens the initial circuit of relay 28. Relay 28 now remains operated in its locking circuit through relay 29, and relay 29 operates. Upon operating, relay 29 applies ground potential to wiper 38 at its lower contacts, through the lower armature of the still operated cut-in relay 25. At the same time, cut-out relay 29 opens the locking circuit through the windings of relays 25 and 24 to permit these relays to restore. Relay 25 is slow in restoring, and therefore maintains wiper 38 grounded through contacts of relay 29 for a substantial fraction of a second in order that an effective impulse be delivered through wiper 38 to a selected signal; in case the wiper of this selector has been positioned on a contact with which a signal is associated.

When relay 24 restores, which occurs prior to the restoration of relay 25 because of the relatively stiff adjustment of relay 24 compared to the adjustment of relay 25, it opens a further point in the previously existing locking circuit of the two relays.

When relay 25 restores, it disconnects ground potential from wiper 38 so as to prevent the inadvertent grounding of signal contacts over which this wiper may pass in restoring to normal position. Relay 25 also transfers the armature of line relay 21 back to the timing relays 22 and 23 at its upper armature, while at the normally closed contacts associated with its lower armature it closes a circuit through off-normal contacts 34 for release magnet 33. By the operation of release magnet 33, the wiper 38 is caused to restore to its normal position and the off-normal contacts 34, 35, and 36 return to the normal condition illustrated in the drawing. At off-normal contacts 34, the circuit of release magnet 33 is opened, while at off-normal contacts 36 the circuit of relays 28 and 29 is opened to permit these relays to restore. The selector S1 is now restored to normal position and is also removed from under control of line relay 21 by the described restoration of relay 25.

It will be understood, of course, that some contacts in the bank of the switch S1 are connected to signals, while non-corresponding bank contacts in the bank of the switch S2 are connected to signals at signal station C. As many signals as desired may be provided at either signal station, within the limits of the capacity of the selectors. By way of illustration, three signals are shown at station A, connected to bank contacts 12, 13, and 14 (corresponding to numbers 12, 13, and 14 as called from the calling device 3.) It will be understood that the contact bank 39 is wired by means of separate conductors to terminals in the terminal block 49 which terminals may be suitably marked to indicate the contacts with which they are respectively connected. The signal relays such as 51, 52, and 53 which are provided at the station are wired to terminals in a block such as 41, and jumper wires 42 connect the terminals in block 41 to assigned ones of the terminals in block 40, according to any desired numbering arrangement.

Assuming now that wiper 38 of the selector S1 has been set on the fourth contact of the first level (in response to dialling the number 14), the momentary application of ground potential to the selected contact which is made as hereinbefore described results in the momentary closure of a circuit over the associated one of the jumper conductors (42) and through the

- relay 51. Relay 51 operates and locks itself through the release push-button 55 and the common signal relay 56. Relay 51 also closes a lighting circuit for the individual signal lamp 54 to notify the attendant of the identity of the signal relay operated. Relay 56 closes a circuit through the signal buzzer 57 to call the attendant's attention audibly to the fact that a signal has been operated.
- 10 After the attendant has taken note of the operated signal, he may restore the signal apparatus to normal condition by momentarily depressing button 55, whereupon relay 56 restores and stops the operation of the buzzer and relay 51 restores and extinguishes the lamps 54, in addition to opening its previously established locking circuit at an additional point so that the locking circuit does not become reclosed when the button 55 is restored.
- 15 By the arrangement illustrated and described, the selector is automatically restored to normal position following the dialling of a desired signal number, with the result that the dispatcher at the transmitting station may (by reoperation 20 of push-button 4), dial several numbers successively, each indicative of a desired signal operation, and the selector S1 will respond to each of the numbers to bring its wiper 38 into engagement with the corresponding contact, and 25 the similar selector S2 at signal station B does likewise. Then, the special signalling operations being completed, the dispatcher at the transmitting station may permit the telegraph transmitter to proceed with the transmission of telegraph messages without further response of the 30 selectors.
- 35 What is claimed is:
1. In combination, a line extending between a transmitting station and a receiving station, a selecting device associated with said line and located between the transmitting station and the receiving station, means for transmitting signals comprising codes of impulses over the line, said device normally being out from under the control of signals transmitted over the line, timing means associated with the selecting device, means for transmitting a special signal of the same character as but of a length not encountered in ordinary transmission over the line, said timing means responsive only to said special signal for placing said selector under the control of the line at the termination of the said special signal, said selector thereafter responsive to signals over the line.
  2. In combination, a line of the normally-closed-circuit type having means associated therewith for transmitting messages thereover by opening and closing the line to send telegraphic signals, means for sending signals having a special significance over said line, a responding device controlled over the line by said special signals,

said responding device being normally out from under the control of the line, means responsive only to a prolonged cessation of current flow over the line preceding the transmission of special signals for placing said device under the control of the line, and means automatically responsive to the operation of said device by said special signals for again removing it from under the control of the line.

3. In combination, a line, a signal station located along said line, a selector at said signal station having a group of contacts, means for sending messages over said line without affecting said selector, a timing device controlled over the line, means controlled by said timing device responsive to a prolonged cessation of current flow over the line for actuating said timing device to bring said selector under the control of the line, means for transmitting selector actuating signals to cause said selector to select a desired contact, and means automatically effective after the selector has selected a contact for removing it from under the control of the line.

4. In combination, a line extending between a transmitting station and a receiving station, a selecting device associated with said line and located between the transmitting station and the receiving station, said device normally being out from under the control of signals transmitted over the line, timing means associated with the selecting device responsive to signals as transmitted over said line, means effective when a special signal of a length not encountered in ordinary transmission is transmitted over the line for placing said selector under the control of the line at the termination of the said special signal, means for operating said selector responsive to selecting signals thereafter received over the line, and means automatically effective after the selector is operated for removing said selector from under the control of the line.

5. In combination, a line extending between a transmitting station and a receiving station, a selecting device associated with said line and located between the transmitting station and the receiving station, said device normally being out from under the control of signals transmitted over the line, timing means associated with the selecting device responsive to signals as transmitted over said line, means effective when a special signal of a length not encountered in ordinary transmission is transmitted over the line for placing said selector under the control of the line at the termination of the said special signal, means for operating said selector responsive to selecting signals thereafter received over the line, and means automatically effective after the selector is operated for restoring said selector to normal position.
